UNITED STATES PATENT OFFICE.

CHARLES E. PHILLIPS, OF INDIANAPOLIS, INDIANA.

FACE-PLATE FOR CONCRETE-BLOCK MACHINES.

1,172,731.

Specification of Letters Patent.

Patented Feb. 22, 1916.

Application filed August 27, 1915. Serial No. 47,655.

To all whom it may concern:

Be it known that I, CHARLES E. PHILLIPS, a citizen of the United States, residing at Indianapolis, in the county of Marion and State of Indiana, have invented certain new and useful Improvements in Face-Plates for Concrete-Block Machines, of which the following is a specification.

This invention relates to face plates employed in machines for manufacturing concrete blocks having their faces divided by grooves to represent binder joints so that brick construction can be imitated with the use of these blocks; and the object of the invention consists in the provision of a face plate of the above character whereby predetermined slots or grooves are formed in the faces of the blocks during their course of manufacture, the slots or grooves being intended to represent the joints formed by the usual binder so that brick construction can fairly be imitated when the blocks are employed in wall construction.

A further object of the invention is to provide a face plate of the above character whereby slots or grooves may be formed in the faces of the blocks during the course of manufacture while the faces of the blocks are down, the means for forming said slots or grooves being removed from the blocks when the latter are turned over on their sides and thereby allowing free and unobstructed removal of the blocks from the machine.

I accomplish the above objects of the invention by means of the construction illustrated in the accompanying drawings, forming a part hereof, in which—

Figure 1 is a cross section of one style of a conventional machine for the manufacture of concrete blocks, showing my improved face plate in operative position during the initial formation of the block. Fig. 2 is a view similar to Fig. 1 except that it shows the block turned over on its side and resting upon the pallet and showing the means for forming the slots removed from the block. Fig. 3 is a plan view of the face plate, the surrounding parts of the machine being omitted. Fig. 4 is a cross section of the face plate, on the line A—A in Fig. 3, showing the groove forming bars extended above the face of the plate. Fig. 5 is a

view similar to Fig. 4, except that the groove forming bars are shown in their retracted position. Fig. 6 is a perspective view of the groove forming bars, the surrounding parts being omitted.

Referring to the drawings, 10 represents one of a pair of side members which support the mold box in which the blocks 11 are formed. The members 10 forming the main frame of the machine are held in their respective relation by means of a stationary back plate 12 and bolts 13, and said plate 12 forms one side of the mold box. The mold box, exclusive of the back plate 12, comprises the face plate 14, end gates 15 and the removable pallet board 16. These latter parts of the mold box are movable through the action of a swinging frame 18 which is pivotally secured to the side members 10 at 19, the machine here shown being of a conventional style in which the operation of molding the blocks is performed with the faces down, so that blocks having irregular faces and blocks having grooves can not only be successfully molded but can be removed from the machine without injury.

As shown in Fig. 3 the face plate comprises a series of sections 14 which are arranged to form a rectangle, the area of the collective sections being equivalent to the surface area of the face of the block. These sections are arranged in their respective relation with uniform intervening spaces 20 within which the groove forming member is situated. The sections 14 are held in position by means of a base plate 22, the former being held in advance of the latter by a plurality of hollow cylinders 24 of uniform length, and passing through these hollow cylinders, sections and base plate are bolts 25 by which all of the parts are held together.

The groove forming member 21 is mounted so as to have movement independent of both the sections 14 and base plate 22 in order that the projecting portion of said member above the surface of the face plate may be retracted or removed from the block after the operation of molding the latter is completed. After a block is removed from the machine and the parts of the latter are resting in the position shown in Fig. 2, the

frame 18, carrying the face plate, end gates 15 and pallet board 16, is moved into vertical position shown in Fig. 1, preparatory to the molding of the next block. During the movement of the frame 18 the face plate is lowered into the position it occupies in Fig. 1, and just before reaching the limit of its travel the ends of the member 21 come into contact with a pair of blocks 30, one of which is located upon each of the side members 10, which arrest the movement of the member 21 slightly in advance of the moving face plate, so that the movement of the latter is sufficiently extended to allow the edges of the groove forming member 21 to project above the surface of the face plate to form grooves 11^a of the desired depth in the next block. After the operation of molding the next block is completed the frame 18 is again lowered into the position shown in Fig. 2, the movement of the frame 18 being arrested by means of an arm 31 engaging the lower edge of the back plate 12, at which time the block is resting upon the pallet board and ready to be removed from the machine. During the operation of turning the block so as to be sustained by the pallet board it is desirable to remove the groove forming member 21 from the newly made block to protect the latter from possible injury by the projecting portion of the member 21 above the surface of the face plate.

Movement is imparted to the groove forming member 21 by means of a lever 35 which is pivoted in a standard 36 at 37, the end of the lever adjacent to the standard pivotally engaging a link 38 which extends over and pivotally engages the member 21 at 40. As has heretofore been pointed out, the movement of the member 21 to project its upper portion above the surface of the face plate is effected by the latter coming into contact with the blocks 30 when the frame 18 is lowered, and it is to retract the member so as to bring it flush with the surface of the face plate that comes within the sphere of action of the lever 35. After the block is molded and the frame 18 is lowered into the position shown in Fig. 2, the free end of the lever 35, immediately preceding the limit of travel of the frame 18, comes into contact with the lower edge of the back plate 12 which forces said end of the lever backward, and through the intermediate fulcrum between the point of contact of the free end of the lever and its engagement with the member 21 through the link 38, the member 21 is moved toward the back plate 12 a sufficient distance to bring the edge of the member 21 flush with the surface of the face plate, leaving the latter smooth and free from obstruction. The newly made block may now be freely removed from the machine.

Having thus fully described my said invention, what I desire to secure by Letters Patent is—

1. The combination, with a concrete block machine-frame, of a face plate comprising a plurality of sections arranged with intervening spaces, a movable member arranged in said spaces for forming grooves in the block, means to move said member in a direction to project its groove forming portion a predetermined distance above the adjacent surface of the face plate, and means to move said member in the reverse direction to bring that portion of the groove forming member flush with the adjacent surface of the face plate when the block is completed. 75

2. The combination, with a concrete block machine-frame, of a face plate comprising a plurality of sections arranged with intervening spaces, a movable member arranged in said spaces for forming grooves in the block, means arranged on the machine-frame for arresting the movement of said member in advance of the face plate for elevating the groove forming portion of said member above the adjacent surface of said face plate, and means for lowering the projected portion of said member when the block is completed. 85

3. The combination, with a concrete block machine-frame, of a face plate comprising a plurality of sections arranged with intervening spaces, a base-plate for mounting said face plate, means for holding said face plate in advance of said base-plate, means for securing the face plate to the base-plate, a movable member arranged in said intervening spaces of the face plate for forming the grooves in the block, means for elevating said movable member a predetermined distance above the adjacent surface of the face plate when the latter is seated, and means for retracting said movable member when the face plate is raised to free the block. 100 105

4. The combination, with a concrete block machine-frame, of a face plate comprising a plurality of sections arranged with intervening spaces, a base-plate, means for holding the face plate in advance of the base-plate, means for securing the face plate and base-plate together, a movable member arranged in the intervening spaces of the face plate, means for projecting the said member partly above the adjacent surface of the face plate, and means for moving said member flush with the adjacent surface of the face plate. 115 120

5. The combination, with a concrete block machine-frame, of a face plate comprising a plurality of sections arranged with intervening spaces, a base-plate, means for holding said face plate in advance of said base-plate, means for securing the face plate and base-plate together, a movable groove form- 125 130

ing member arranged within said intervening spaces in the face plate, means for arresting the movement of said groove forming member in advance of the face plate when the latter is moved into position for the molding of a block, and a lever for returning said member to normal position when the block is completed.

In witness whereof I have hereunto set my hand and seal at Indianapolis, Indiana, on this 20th day of August, A. D. one thousand nine hundred and fifteen.
